UNITED STATES PATENT OFFICE.

OTTO W. HENSEL, OF LINN GROVE, IOWA.

RAILROAD-TIE.

1,186,397.

Specification of Letters Patent.

Patented June 6, 1916.

Application filed October 19, 1915. Serial No. 56,754.

To all whom it may concern:

Be it known that I, OTTO W. HENSEL, a citizen of the United States, residing at Linn Grove, in the county of Buena Vista and State of Iowa, have invented certain new and useful Improvements in Railroad-Ties; and I do hereby declare the following to be a full, clear, and exact description of the invention, such as will enable others skilled in the art to which it appertains to make and use the same.

The object of the invention is to improve the construction of metallic railway ties by providing a tie that will be of simple construction, durable, and cheap to manufacture; also one of such construction that it will admit of wooden blocks being associated therewith so as to form cushion seats for the rails, and one that will be so constructed that the different fastening bolts and rivets, employed, will be relieved of strain.

Other objects will appear and be better understood from that embodiment of my invention of which the following is the specification, reference being had to the accompanying drawings forming a part thereof, in which,

Figure 1 is a side view of the tie, Fig. 2 is a top plan view thereof, Fig. 3 is a vertical sectional detail view taken on the line 3—3 of Fig. 2, Fig. 4 is a section taken on the line 4—4 of Fig. 3, Fig. 5 is a detail perspective view of one end of the tie, with the rail and cushioning block removed therefrom, Fig. 6 is a detail section taken on the line 6—6 of Fig. 2, Fig. 7 is a detail plan of one end of the tie showing a modified form of rail securing plate employed with the tie.

Referring to the drawings, the numeral 1 designates the metallic tie, as an entirety and which is formed of a rectangular hollow body having the bottom wall 2 provided with circular openings 3 and the vertical side walls 4 and 5, the opposite ends and the top of the tie being open. The side wall 4 of the tie has its opposite ends provided with extensions 6, which are folded across the top of the tie, at the opposite ends thereof, and have their free ends bent downwardly as at 7 and positioned against the side 5 of the tie and are secured to the said sides 5 by means of fastening bolts 8. The extensions 6 each have a transverse cut out portion providing an opening 9, the said opening extending across the extensions and into the

downwardly bent portion 7 and the vertical side 5 of the tie is provided at the point adjacent its opposite ends with a pair of vertical slits which open into the upper edge 60 of the vertical wall 5 and form bendable tongues 10 which extend through the openings 9 and are folded over against the ends 7 of the extensions 6. By virtue of these bendable tongues 10, the fastening bolts 8 65 will be relieved from considerable strain.

Associated with the metallic tie 1, is a pair of wooden blocks designated 11. These blocks are positioned within the tie and are located at the opposite ends thereof and underlie the openings 9 in the respective extensions 6, the said blocks being of a height slightly less than the height of the tie and each has its upper side provided with a longitudinally extending groove 12, the said groove opening into the upper side of the block and into the opposite ends thereof. Metallic rectangular shaped plates 13 are superposed upon the upper side of the rectangular blocks 11 and are adapted to snugly 80 fit between the blocks and the under surfaces of the adjacent extensions 6. These plates 13 serve as seats for the rails 14 and by virtue of the employment of the wooden blocks 11, the desired cushioning effect for the rails 85 14 will be attained.

The extensions 6 are each provided on opposite sides of the transversely extending openings 9 with circular openings 15, which register with similar openings in the rectangular metallic plates 13 and admit of spikes 16 being inserted through the extensions 6, the metallic plates 13 and the wooden blocks 11 so as to hold the plates 13 and blocks 11 in their operative position.

Each of the extensions 6 has a pair of substantially semi-circular cut out portions 17 which are located opposite each other and open into the opening 9 in the extension. Rail fastening plates designated 18 are positioned on opposite sides of the base flange of each rail 14, and each has one end positioned within the adjacent semi-circular cut out portion 17 and shaped to conform to the cut out portion and has its upper side lying flush with the upper side of the adjacent extension, the opposite end of the fastening plate being bent to provide a rail engaging flange 19. Headed bolts 20 have their shanks threaded and extended through the plates 13 and through those ends of the fastening plates 18 located in the semi-cir-

cular cut out portions 17 and have their upper ends received by nuts 21 which are adjustable against the adjacent ends of the plates 18. The heads of the bolts 20 are loosely received by the groove 12 in the wooden blocks 11 so as to admit of the convenient removal or insertion of the wooden blocks. When it is desired to remove the blocks 11 from the tie, so as to substitute new ones, the spikes 16 are withdrawn and the blocks 11 slid outwardly by means of any suitable tool.

In the modification shown in Fig. 7, the extension 6 is shown provided with elongated transversely extending recesses 22, one side of each recess opening into the adjacent opening 9. In this figure the rail fastening plates are shown as angular shaped, each having one arm thereof designated 23 inserted within one of the recesses 22 and secured therein by means of the headed bolt 20 and nut 21, and also by means of a fastening spike 24 which extends through the arm 23 and through the plate 13 and wooden block 11. The other arm of the fastening plate 18 designated 25, extends beyond the recess 22 and is terminally flanged for engagement with the base flange of the rails 14.

From the foregoing description taken in connection with the accompanying drawings, it will be seen that I have considerably improved the construction of metallic ties so that the desired cushioning effect can be had for the rails and to admit of the operation of the removal of the wooden blocks from the casing to be expeditiously carried out and also to relieve the different fastening bolts, and spikes which are employed with the tie from considerable strain.

Having thus described my invention what I claim as new is:

1. A rail tie comprising a hollow rectangular shaped body having its upper side open, extensions formed on one side wall of the body and foldable over the top of the body, the said extensions having transversely extending openings therein, blocks located within the body and underlying the openings, rails positioned on the top of the body and having their base flanges received by the openings and resting on the block, bendable tongues carried by the other side wall of the body and extending through the transverse openings in the extensions, and rail fastening plates located on the upper side of the body and engaging the rails.

2. A rail tie comprising a hollow rectangular shaped metallic body having its top open, extensions formed on the opposite ends of one of the side walls of the body, and foldable over the open top of the body,

each of the extensions having a transversely extending opening therein adapted to receive the base flange of a rail and having substantially semi-circular cut out portions located opposite each other and communicating with the transverse opening, plates located on the under side of the extensions and underlying the openings and the semi-circular cut out portions and also engaging the upper surface of the block, rail fastening plates positioned on the opposite sides of the transverse openings and each having one end resting on the adjacent rectangular plate and received by one of the adjacent semi-circular cut out portions in the extensions and bolts extending through the rectangular plates and the rail engaging plates, for holding the latter in operative position.

3. A rail tie comprising a hollow rectangular shaped metallic body having its top open, angular shaped extensions formed on one side wall of the body and foldable over the top of the body and against the opposite side wall of the body and provided with transversely extending openings, adjustable tongues formed on the last mentioned side wall of the body and extending through the transverse openings in the extensions and foldable against the said extensions and fastening elements extending through the last mentioned side wall of the body and through the extensions and located on opposite sides of the tongues.

4. A rail tie comprising a hollow rectangular shaped metallic body having its top wall open, extensions formed on one of the side walls of the body and foldable over the top of the body, said extensions having transversely extending openings therein and having transversely extending recesses located adjacent the transversely extending openings and communicating with the openings, rail supporting blocks positioned within the body and underlying the extensions, angular shaped rail fastening plates associated with the hollow body and each having one of its angular arms positioned within one of the recesses and having its other arm flanged and adapted to engage over the base flange of a rail, fastening means extending through the arms located within the recesses and engaging the rail supporting blocks.

In testimony whereof I affix my signature in presence of two witnesses.

OTTO W. HENSEL.
